UNITED STATES PATENT OFFICE.

AUGUSTUS J. PENOTE, OF CLEVELAND, OHIO.

DITCHING MACHINE.

Application filed January 18, 1923. Serial No. 613,436.

To all whom it may concern:

Be it known that I, AUGUSTUS J. PENOTE, a citizen of the United States of America, residing at Cleveland, in the county of Cuyahoga and State of Ohio, have invented certain new and useful Improvements in Ditching Machines, of which the following is a specification, reference being had therein to the accompanying drawings.

10 This invention relates to ditching machines, such as are commonly employed to excavate trenches wherein pipe lines or the like may be laid.

15 It is an object of the invention to provide a ditching machine having a considerably lighter and more compact construction than has heretofore been employed in such a machine, these characteristics making it feasible to operate the machine upon a cement 20 sidewalk without damage to the latter or within the comparatively narrow confines of the space ordinarily intervening between curb and sidewalk in residence districts.

25 One of the features contributing to the light construction is the use of belt type traction elements and the elimination of steering wheels.

30 A further feature is the novel provision for shifting the excavating wheel toward the center of gravity of the machine as said wheel is raised to stored position, so as to minimize the total length of the machine under traveling conditions.

35 The invention further consists in other structural features hereinafter fully described and illustrated in the accompanying drawings, wherein:—

40 Figure 1 is a view of the improved machine inside elevation, showing in full lines the lowered or working position of the excavating wheel and indicating the raised or stored position thereof in dash lines;

45 Figure 1^a is a fragmentary view showing the engagement of the arms for supporting the excavating wheel with a vertically 50 slideable pivot member;

Figure 1^b is a section on line 1^b—1^b of Figure 1^a;

55 Figure 2 is an elevation of the other side of said machine, certain parts of the driving mechanism being broken away;

Figure 3 is a plan view thereof;

Figure 3^a is a detail, in partial section, of a double acting clutch mechanism shown in Figure 3;

Figure 3^b is a sectional detail of another clutch mechanism shown in Figure 3, and serving to reverse the drive through the clutch of Figure 3^a;

Figure 4 is a rear end view;

Figure 5 is a cross-section on line 5—5 of Figure 1 showing primarily the cutter wheel and its drive mechanism;

Figure 6 is a diagram of the various chain drives through which the vehicle is propelled, the cutter wheel rotated, and the lifting and lowering cables for said wheel energized;

Figure 7 is a diagrammatic plan view of the same.

In these views the reference character 1 designates a pair of sill members formed preferably of channel bars, the same supporting a superstructure comprised of angle bars 2 constituting the main frame of the machine. The frame thus formed is carried upon a sub-frame composed of cross bars 3 and sub-sills 4, the latter extending at each side of the machine and carrying at their ends bearings 5 mounting stud shafts 6 extending from sprocket wheels 7 having driving engagement with belt type traction belts 8. The forward portion of the main frame 1, 2 projects preferably considerably beyond the described running gear and provides a mounting for an internal combustion engine 9 furnishing power for driving the described running gear and the excavating wheel 10, and for raising and lowering the latter when desired. The distribution of power for the purpose specified is effected from a counter shaft 39 to which the engine shaft 37 is connected by a chain 38.

The adjustable mounting of the excavating wheel comprises a pair of elongated arms 11 rigidly connected and spaced to accommodate between them the upper portion of said wheel, the forward end of said arms being pivoted, as indicated at 12, upon a carriage 13 vertically adjustable upon posts 14 comprising a rear portion of the main frame 2. Said posts incline forwardly at a considerable angle so that an adjustment of said carriage 13 upwardly to establish the stored position of the parts accomplishes also a for-

ward shifting of the arms 11 and excavating wheel. Said wheel, as is common practice, has the form of an annulus interiorly journaled upon rollers 15 arranged at the apices 5 of a triangular frame 16 secured to and depending from the arms 11. 17 designates the usual series of combined cutters and bucket members peripherally carried by the excavating wheel. 18 is the usual belt conveyor extending transversely through the cutter wheel above the arms 11 and mounted upon pulleys 19 attached to the arms 11 by rods 20.

The means for elevating the excavating 15 wheel comprises a pair of cables 21 passing around sheaves 22 secured to the rear or free ends of said arms, said cables having corresponding extremities anchored, as indicated at 23, to the upper extremities of 20 the posts 14 and having strands extending over pulleys 24 surmounting said posts and thence passing to a pair of drums 25 fast upon a shaft 26. Said shaft is adapted to be driven from the counter-shaft 39 through a worm and worm wheel 26^a and 26^b, a chain 27 and a shaft 27^a. Adjacent and parallel to the drums 25 there is mounted another pair of drums 28 to which a driving connection from said counter-shaft is established through the worm and worm wheel 29 and 29^a, a chain 30, and the shaft 27^a. The drums 28 carry cables 31 for raising or lowering the pivotal support 13, said cables passing over sheaves 32 carried by the uprights 14, then passing around sheaves 32^a carried by the inner ends 35 of the arms 11 and being finally attached to said uprights at 32^b. The drive connection to the drums 25 and 40 28 is established through a common clutch element 33 slidable upon the shaft 27^a to alternatively engage the clutch disks 35 and 36 for selectively establishing a drive to the drums 25 or 28. Provision is made for 45 reversing the direction of drive to the shaft 27^a. Thus a bevel gear 27^b, fast upon the rear end of said shaft, is adapted to be driven selectively by either of two bevel gears 27^c loose upon the shaft 39, and alternatively engageable by a double acting clutch member 27^d splined upon said shaft between said gears 27^c (see Figure 3^b).

Tracing now the drive from the counter-shaft 39 to the excavating wheel, 40 is a chain, driven from said counter-shaft and driving a sprocket wheel 41 journaled upon the frame 2. From the last-mentioned sprocket wheel a chain 42 drives a shaft 43 transversely mounted upon the arms 11 and carrying drive wheels 44 engaging a gear 44^a comprised by laterally projecting teeth on the excavating wheel. Upon the arms 11 there is longitudinally mounted a shaft 45 driven from the shaft 43 and having drive connection through a chain 46 to one

of the pulleys 19 mounting the conveyor belt.

The running gear is driven from the counter-shaft 39 through a chain 47^a and through other mechanism which involves 70 no novelty and consequently no description of the same is here required.

It will be observed that in the stored position of the excavating wheel the same overhangs the machine at the rear end, 75 counterbalancing the overhanging forward portion of the machine which carries the engine. By virtue of this counterbalance arrangement the longitudinal extent of the machine under traveling conditions is considerably reduced as compared to machines heretofore employed for a like purpose. A further advantage of employing the described belt type traction element lies in the distribution of the weight of the machine 80 to an extended supporting surface so that the concentration of the load when the same is distributed to the sidewalk or other surface whereon the machine is traveling will not be sufficient to result in damage to said 85 surface.

Employment of a single clutch member to control the drive connection to the drums receiving the cables for respectively raising the forward and rear ends of the arms 95 carrying the excavating wheel simplifies the control of the machine.

What I claim as my invention is:

1. An excavating machine comprising an excavating wheel, a mounting for said wheel, a post inclining from bottom to top toward a perpendicular through the center of gravity of the machine, and means for adjusting said mounting longitudinally upon said post. 100

2. An excavating machine comprising an excavating wheel, a mounting for said wheel, a pivotal support for said mounting, and a post inclined from bottom to top toward a perpendicular through the center of gravity of the machine upon which post said pivotal support is adjustable up and down. 110

3. An excavating machine comprising a vehicular frame, an excavating wheel, an elongated mounting for said wheel pivoted at one end to provide for angularly raising and lowering said frame, a pivotal support for said mounting, guide means for said pivotal support rising from said frame at an inclination toward a perpendicular through the center of gravity of the machine, and means for adjusting said pivotal support up and down upon said guide means. 115

4. An excavating machine comprising an excavating wheel, a supporting element therefor, a vehicular frame, said element being located endwise of said frame, and means carried by said frame for guiding 120

the said supporting element upwardly and forwardly toward a perpendicular through the center of gravity of the machine.

5. An excavating machine comprising an excavating wheel, an elongated supporting element for said wheel, a carriage adjustable upwardly and downwardly in a direction oblique to the upper surface of the machine, said supporting element being

pivoted to said carriage, cables for raising and lowering the respective ends of said element, drums engaged by said cables, driving means for said drums and a clutch element adjustable to alternatively establish a drive to said drums. 15

In testimony whereof I affix my signature.

AUGUSTUS J. PENOTE.
